UNITED STATES PATENT OFFICE.

JOHN R. WHEELER, OF EDENTON, NORTH CAROLINA, ASSIGNOR OF ONE-FOURTH TO CARROLL W. BRINKLEY AND ONE-FOURTH TO ROBERT G. WHITE, BOTH OF EDENTON, NORTH CAROLINA.

STAPLE.

984,629.

Specification of Letters Patent. Patented Feb. 21, 1911.

Application filed April 25, 1910. Serial No. 557,531.

To all whom it may concern:

Be it known that I, JOHN R. WHEELER, citizen of the United States, residing at Edenton, in the county of Chowan and State 5 of North Carolina, have invented new and useful Improvements in Staples, of which the following is a specification.

My invention has to do with staples of the two-prong type such as are designed for attaching wire runners to fence posts; and it 10 has for its object to provide a staple of the kind stated embodying a body adapted to give it increased strength and also adapted to form a wide seat for a wire runner and to 15 be embedded in a fence post to a slight extent with a view to holding the staple against upward and downward movement under pressure imposed against the runner, and also embodying a head on the body designed 20 to afford means for the connection or application of pliers or the like through the medium of which the staple may be conveniently withdrawn when occasion demands.

With the foregoing in mind the invention 25 will be fully understood from the following description and claim when the same are read in connection with the drawings, accompanying and forming part of this specification, in which:

30 Figure 1 is a side elevation of my novel staple. Fig. 2 is a plan view of the same. Fig. 3 is a transverse section taken in the plane indicated by the line 3-3 of Fig. 1. Fig. 4 is an elevation of the head end of the 35 staple. Fig. 5 is a perspective view of the staple.

Similar letters designate corresponding parts in all of the views of the drawings, referring to which:

40 A A are the prongs of the staple, which are pointed at *a*, and B is the staple body which is integral with the prongs. The said body B is of increased width—*i. e.*, it extends laterally in opposite directions from 45 the plane in which the two prongs lie; and it is provided in its inner side with a wide bight *b*, designed to receive a wire fence-runner, and is also provided at opposite sides of the prongs and as best shown in Figs. 2 and 3, with beveled end portions *c*. These beveled end portions *c* are designed when the 50 staple is driven into a fence post, to be embedded in the post to a slight extent, as indicated by the upright dotted line *d* in Fig. 51, which dotted line represents the face of

the post, this in order that when the staple is positioned in the post and the runner is arranged in the wide bight *b* of the staple, the said slightly embedded end portions *c* of the body will effectually prevent upward or 60 downward movement of the body and the staple as a whole under upward or downward pressure imposed against the runner, and by so doing will remove strain from the prongs A and prevent the same working 65 loose in a vertical direction in the post.

In addition to the prongs A and the body B, the one-piece staple comprises a head C which is connected by a neck *e* to the body, and hence affords means for the application 70 of an implement through the medium of which the staple can be conveniently withdrawn from the post when desired. It will also be noted in this connection that the head C is adapted to receive the blows of a hammer employed in embedding the staple in 75 the post.

It will be gathered from the foregoing that the body B of increased width lends strength to the staple as a whole, and forms 80 a broad holder for the fence runner, and one which because of its breadth will not be liable to cause breakage of the runner at the point where the same is engaged by the staple; and it will also be noted that notwithstanding the adaptability of the beveled ends *c* of the body to be embedded to a slight extent in the post, the body B serves by abutting against the post to limit the inward movement of the staple. 85

Having described my invention, what I claim and desire to secure by Letters Patent, is:

A staple formed in one piece and comprising prongs, a body of increased width extending at opposite sides of the plane in which the prongs lie and having a bight in communication with the space between the prongs and also having beveled end portions at opposite sides of the rear ends of the 100 prongs, a head at the outer side of the body, and a neck joining the said head to the body. 95

In testimony whereof I have hereunto set my hand in presence of two subscribing witnesses.

JOHN R. WHEELER.
